UNITED STATES PATENT OFFICE.

SAMUEL S. BLOOM, OF PHILADELPHIA, PENNSYLVANIA.

ARTIFICIAL TOOTH AND ANCHOR.

SPECIFICATION forming part of Letters Patent No. 717,158, dated December 30, 1902.

Application filed November 9, 1901. Serial No. 81,748. (No model.)

To all whom it may concern:

Be it known that I, SAMUEL S. BLOOM, of Philadelphia, in the county of Philadelphia and State of Pennsylvania, have invented 5 new and useful Improvements in Artificial Teeth and Anchors Therefor; and I do hereby declare the following to be a full, clear, and exact description of said invention, reference being had to the accompanying drawings, and 10 to the letters of reference marked thereon, which form a part of this specification.

One of the means for connecting artificial teeth with the plate or support therefor involves the use of pins the anchorage of which 15 is inserted in the tooth before baking. As most metals fuse under the temperature required to bake the porcelain of which the teeth are made, platinum is usually employed. Sometimes the pins are integral with the anchorage and are made entirely of platinum; but as this metal is expensive attempts have 20 been made to make the anchors only of platinum and to secure pins of German silver and other metal cheaper than platinum to said 25 anchors. Difficulty has been experienced in obtaining a firm and durable union between the silver pins and the platinum anchors, and difficulty has also been experienced in properly locating the anchors in the molds in which 30 the teeth are baked.

The object of this invention is to provide an improved anchor which can be given its proper location by means of the old and well-known form of mold in which holes are formed 35 for the reception of pins, said anchor affording means for a perfect soldered connection with the pins of German silver or other suitable metal and for steadyng and protecting said pins. This object is accomplished by 40 causing the anchor-tube to project beyond the tooth-body to afford a more secure bearing for the pin that is to be soldered therein.

To these ends the invention consists in the anchors and in the connection therewith of 45 pins, substantially as hereinafter described and claimed.

In the drawings, Figure 1 represents a section of a tooth greatly enlarged and showing one form of the platinum anchor embedded 50 therein. Fig. 2 represents a similar view showing a pin in the position which it occupies when secured to the anchor and the tooth.

Fig. 3 represents a detail section of the anchor shown in Figs. 1 and 2. Figs. 4 and 5 represent, respectively, an enlarged section 55 and a perspective view of modified forms of anchors.

Similar reference characters indicate the same parts throughout the several views.

One form of artificial tooth is represented 60 at *a*, and what is commonly known as the "pin-flange" thereof is represented at *b*.

The platinum anchor is represented at *c*, and *d* represents a pin having a head *d'*, which pin is secured in the anchor by solder, the 65 head of said pin being adapted to be embedded in the plate to which the tooth is attached. The anchor consists of a flaring or tapering shell of metal, such as platinum, which is fusible only at a temperature higher 70 than that required to bake the material of which the tooth is made. As shown in Figs. 1, 2, and 3, the anchor is formed of a hollow shell, which is flared or tapered slightly and uniformly from end to end. As represented 75 in Fig. 4, the flaring or tapered shell may be shorter than represented in the other figures, and in this case it is formed with an extension *c'*, the walls of which are parallel. The anchor represented in Fig. 5 is similar in shape 80 to that shown in Fig. 3; but it is cut away or formed with an open space along one side in order to save metal.

In using any one of the forms of anchor shown in the drawings the anchors are or may 85 be placed in the molds with the small ends resting in the holes provided in such molds for the ordinary purpose of holding pins. The larger ends of the anchors project into the cavities of the molds which are filled with tooth material. 90 The anchors are then preferably filled with wax or other suitable material which will prevent the tooth material from entering the anchors. The cavities of the molds are filled and the teeth are baked in the usual manner. 95 During the baking operation the wax, if such is employed, will be burned out, leaving the space inside of the anchors ready to receive the pins, as presently described. After the teeth are baked and are removed or delivered 100 from the molds in the ordinary way a small amount of solder may be inserted in the anchors and the pins *d* pushed therein, as represented in Fig. 2. Owing to the flared or

larger inner ends of the anchors, sufficient space is left around the inner ends of the pins to firmly hold said pins without exuding from the anchors. The smaller ends of the anchors 5 project from the pin-flange substantially as represented. This steadies and strengthens the pin, and when said anchors project far enough practically the entire stem of the pin will be covered with the platinum, and hence 10 there is less liability of the silver of the pin or the silver solder which is employed causing the rubber plate to become spongy around the pin.

Having thus described my invention, what 15 I claim as new is—

1. An artificial tooth having an internally flaring or tapering shell of metal embedded

therein with its smaller end projecting therefrom, whereby an extended bearing and a protection is afforded for the pin. 20

2. An artificial tooth having an internally flaring or tapering shell of metal embedded therein with its smaller end projecting therefrom, and a pin having one end soldered in the shell and the other end projecting therefrom, whereby an extended bearing and a protection is afforded for the pin. 25

In testimony whereof I affix my signature in presence of two witnesses.

SAMUEL S. BLOOM.
